UNITED STATES PATENT OFFICE.

CHARLES C. MURRAY, OF CHICAGO, ILLINOIS, ASSIGNOR TO CUMMINS PERFORATOR COMPANY, OF CHICAGO, ILLINOIS, A CORPORATION OF ILLINOIS.

CRYPTOGRAPHIC MARKING MEANS.

Application filed February 20, 1922. Serial No. 537,810.

To all whom it may concern:

Be it known that I, CHARLES C. MURRAY, a citizen of the United States, residing in Chicago, in the county of Cook and State 5 of Illinois, have invented a new and useful Improvement in Cryptographic Marking Means, of which the following is a specification.

The object of this invention is to enable 10 characters to be punched or otherwise marked upon slips of paper, such as bank checks, sales tickets, labels, wrappers, cartons or other papers, by an improved system of cryptographic notation, the key to which 15 is based upon the characters of an ordinary clock dial, so that, with the mere knowledge of the arrangement of the ordinary clock dial, any authorized person may instantly read the characters represented. Although 20 the characters represented by the cryptographic notation of the invention will be unintelligible to persons not familiar with the key, nevertheless, because of its simplicity, the key to the reading of the characters 25 may be readily imparted to any authorized person, who will thereby be instantly enabled to decipher any of the characters represented, without recourse to code books, or 30 to any other aid to deciphering code notation. The invention is, moreover, readily adaptable to secret code notation inasmuch 35 as the characters represented may be read in conjunction with a clock dial key arbitrarily set a number of hours slow or fast and, consequently, only those persons familiar 40 with the arbitrary setting would be enabled to decipher the characters.

In addition to the general objects recited 45 above, the invention has for further objects 40 such other improvements or advantages in operation and results as may be found to obtain in the devices hereinafter described or claimed.

In the accompanying drawings, forming 45 a part of this specification, there is shown 40 a machine for perforating cryptographic notation, in accordance with the invention, upon slips of paper such as bank checks, sales tickets, labels, wrappers, cartons, and 50 the like. It will be understood, however, that the invention may be embodied in numerous ways and that the notation may be marked by other means than by perforators.

Hence, the invention is not confined in its 55 scope to perforating the notation, nor to the

specific embodiment of machine which is herein described merely as an illustrative example.

Referring to the drawings:

Figure 1 is a perspective view of a perforating machine equipped with punching mechanism designed for perforating characters for carrying out the cryptographic notation of the invention;

Figure 2 is a diagrammatic plan view of 65 the arrangement of the dies in the die plate through which the punches pass in perforating the characters;

Figure 3 is a diagrammatic plan view showing the arrangement of the markers or 70 punchers, as will be hereinafter explained; and

Figure 4 is another diagrammatic view showing the arrangement of the characters and matrices on the matrix rings. 75

Figure 5 is a transverse vertical sectional view through the lower portion of the machine and illustrating more in detail the construction and arrangement of the several punches and the actuating mechanism there- 80 for.

The perforating machine adapted for practicing the cryptographic notation of the invention embodies in its construction a base block 11 provided at its forward end with 85 a horizontally extending open ended slot 12, into which the sheet or sheets of paper to be perforated are inserted. The horizontal surface below the slot 12 is employed as the die plate 13, the dies of which may communicate with the usual chamber (Figure 5) for discharge of the punched out particles of paper.

In the present embodiment of the invention, the die plate 13 is shown as having two 95 sets of die holes A, B for cooperation with two sets of punches and two sets of matrix rings. It will be noted, however, that the number of sets of coacting die holes, punches and matrix rings may be varied as desired. 100 In some instances, it may be best to employ at least three sets of such coacting instrumentalities; whereas, in other cases, one set will suffice, for the reason that the complete cryptographic notation can be practiced, 105 within the limits of the matrices on the matrix rings, with only one set of die holes and punches.

As shown in Figure 2, each set of die holes A or B comprises a center locator die hole c, 110

for locating the center of the circle or periphery P that is representative of a clock dial. Arranged around the circle P are 12 die holes respectively occupying the positions of the ordinary clock dial figures, as clearly shown in Figure 2, that is to say the peripheral die holes are arranged in a circle about the center located die hole c , and at equal distances apart. Those peripheral die holes which occupy the same positions as the digits 1 to 9 inclusive on an ordinary clock dial are employed, in the cryptographic notation of the invention, as indicative die holes i , for selectively representing any digits from 1 to 9 inclusive. The peripheral die hole occupying the clock dial position of the number 11 is employed as the peripheral locator die hole p ; the die hole occupying the dial position of the number 12 is employed as a double indicator die hole d for indicating to the reader that any digit punched by a single selected digit indicator die hole i is to be read twice; for example, should the double indicator hole appear in conjunction with a hole occupying the digit indicator position "3," the reading would be "33." The peripheral die hole occupying the dial position of the number 10 is employed as the reverse indicator die hole r and a hole punched in the reverse indicator position notifies the reader that of two digit indicator holes punched in the same peripheral set of digit indicators, the larger digit is to be read first; for example, should holes occupying the "2" and "3" digit indicator positions appear simultaneously in a single punching operation in conjunction with the reverse indicator hole, the reading would be "32"; without the reverse indicator hole, the reading would be "23." For locating the diameter of the dial, preferably the vertical diameter projected through the "12" and "6" dial positions, there is provided a vertical diameter locator die hole v , the same operating in conjunction with its corresponding punch to punch the vertical diameter locator hole at each punching operation, in order to avoid any confusion in reading the digit indicator holes punched. The center locator die hole c , peripheral locator die hole p and the vertical diameter locator die hole v of each die set comprise the universal locator die holes of their respective die hole sets and punches are provided which co-operate with these universal locator die holes during each punching operation for punching holes which provide the locator or "key" to the reading of the indicator holes which may be selectively determined at the will of the operator. In order to avoid confusion of the locator holes or marks with the indicator marks, the die holes and their corresponding punches for punching the locator holes are preferably designed so as to differentiate

the locator holes or marks from the indicator holes or marks. Such visual differentiation may be satisfactorily attained by making the locator die holes and punches of somewhat larger diameter than the indicator dies and punches. 70

The punches 14 are arranged in two sets A' and B' corresponding with the two sets of dies A and B . Referring to Figure 3, each set of punches A' or B' is arranged to 75 correspond and coact with its corresponding set of dies; for this purpose, each set of punches comprises the relatively larger center locator, peripheral locator and vertical diameter locator punches c' , p' and v' , the 80 relatively smaller digit indicator punches i' , the double indicator punch d' , and the reverse indicator punch r' . In Figure 3, the locator punches are shown in solid black, the digit indicator punches in plain cross-hatching, the double indicator punch by stippling, and the reverse indicator punch by double crosshatching. The locator punches c' , p' and v' of each set of punches are universal or key punches and operate 85 at each punching operation, but the remaining punches may be selectively operated for perforating the particular character to be represented. 90

In the machine illustrated in the drawings, both sets of punches A' and B' extend into a chamber in the base block 11, and the lower ends of said punches, when advanced into their corresponding die holes, project through the perforate guide block 100 16 located below the chamber 15 and forming the top of the paper-receiving slot 12. When in the retracted position, the upper ends of the punches extend through a top 105 guide plate 17 which forms the top of the chamber 15. 110

The punches 14 are operated by adjustable or revolvable matrices 18, there being a pair of such matrices for each set A and B of said punches 14. Each pair of adjustable matrices 18 is constituted of a pair of rings one revolving within the other, and the inner ring upon a non-rotative arbor 19 mounted to slide vertically within the casting 20 of the machine. The matrix rings 115 18 are provided with series of matrix faces 21, as shown by the diagram in Fig. 4, the matrix faces 21 being reversely socketed, so that they will not operate those punches of the group or set which are not required 120 for printing the particular character desired. It will be understood that the matrix faces 21 of each set or pair of matrix rings 18 are sufficient in number and so arranged that any desired permutations of the 125 code system of notation hereinabove described may be punched. The matrix rings 18 are held in proper position for the operation of each of their matrix faces by positioning plugs 22 which extend through slots 130

in the rings and into retaining slots 23 in the arbor 19. When the positioning plugs 22 are seated within the slots of their respective matrix rings and the arbor slot 23, 5 a matrix face 21 of each ring is in proper position for operating its corresponding set of punches.

The positioned matrix faces 21 of the rings 18 are advanced to push forward the 10 selected indicator punches of the groups or sets A and B, as well as the universal locator punches, when the matrix rings are lowered by a lowering movement of the arbor 19. The arbor 19, which is maintained normally in an elevated position, is 15 provided with a cam recess 24. Mounted on a shaft 25 projecting through the arbor and the casing is an eccentric 26 engageable with the surface of the cam recess 24 for 20 lowering the arbor and the matrix rings. The eccentric 26 may be operated by the operating handle 27 secured to the shaft 25. Any suitable means may be provided for maintaining the arbor 19 and the matrix 25 rings in the normal elevated position. As the positioned matrix faces 21 advance the selected punches into their corresponding dies, those punches of the sets A' and B' which are not required to effect the perforation of the particular character remain 30 stationary, the reverse sockets in the positioned matrix faces 21 moving to position the upper ends of the inactive punches in said sockets.

35 On the upward movement of the arbor 19 and the matrix rings 18, the previously operated punches of both series A' and B' are concurrently restored to their normal position. For this purpose, each punch is 40 provided with a fixed collar, indicated by dotted lines at 28, adapted to be engaged by the upper face of a perforate plate 29 through which the several punches 14 extend. The plate 29 is supported by side 45 members 30 depending from the arbor 19, and as the latter moves upwardly, the upper face of the plate engages the collars 28 of the several previously operated punches and restores them to their normal retracted 50 positions.

In carrying out the invention, if the operator desired to punch a cryptogram indicative of the number "1286," the operator by 55 retracting the plugs 22 from the arbor slot 19 manipulates the matrix rings 18 so that the holes opposite the numbers "1" and "2" of one pair of rings are moved into registry with the arbor slot 23 and so that the holes opposite the numbers "6" and "80" of the 60 other pair of matrix rings are also moved into registry with the arbor slot 23. The plugs 22 are then reinserted into the arbor slot 23 to lock the matrix rings in the set position. The paper is inserted into the 65 slot 12 and the matrix rings are lowered by

operating the handle 27, to cause the punches to advance through the paper and into their respective die holes. The paper so punched will be provided with two cryptograms, the one on the left indicating the number "12" by 70 having the digit indicator holes corresponding to the clock dial positions "1" and "2" which may be readily located by reference to the universal locator holes punched by the locator punches c', v' and p', and the cryptogram on the left indicating the number "86" by 75 indicator holes corresponding with the clock dial positions "8" and "6" which when taken in conjunction with the reverse indicator hole corresponding with the "10" clock 80 dial position causes the operator to read the digit "8" before the digit "6." Should an operator desire to punch a number having two of the same digits, such as the number "11," one matrix ring of a pair will be manipulated to set one matrix ring for punching the number "1" and the other matrix ring will be set with the hole opposite the character "D" in registry with the arbor 85 slot 23. After punching the paper, the indicator hole corresponding to the clock dial position "1" will appear in conjunction with the double indicator hole corresponding to the clock dial position "12," whereupon the reader will read the digit "1" twice, making 90 the reading "11."

In accordance with the invention, there is thus provided a cryptographic notation, the key to the reading of which is the ordinary 100 clock dial. The locator markers or punches indicate the dial itself and the selective indicator punches indicate the reading of the dial, in accordance with the system of notation. By means of the reverse indicator punch and the double indicator punch, an 105 entire series of numbers from "1" to "99" inclusive may be indicated cryptographically by each set of punches and coacting dies.

The invention as hereinabove set forth is embodied in a particular form of construction, but may be variously embodied within 110 the scope of the claims hereinafter made.

1. A cryptographic marking means, comprising: universal locator markers for locating respectively the center, periphery, and vertical diameter of a clock dial, combined with a set of selective individual indicative markers, the set of said indicative markers being located in the "1" to "9" clock dial positions of the dial located by the aforesaid 115 locator markers, so that, by noting the positions of the various indicative marks produced by said indicative markers relatively to the universal locator marks, the reader may decipher the cryptogram represented. 120

2. A cryptographic marking means, comprising: universal locator markers for locating respectively the center, periphery, and vertical diameter of a clock dial, combined with a set of selective digital indicative 125

130

markers, the set of said indicative markers being located in different dial positions on the dial located by the aforesaid locator markers, so that, by noting the positions of the 5 various indicative marks produced by said indicative markers relatively to the universal locator marks, the reader may decipher the cryptogram represented.

3. A cryptographic punching means, comprising: universal locator punching devices for locating respectively the center, periphery, and vertical diameter of a clock dial, combined with a set of selective individual indicative punching devices, the set of said 10 indicative punching devices being located in the "1" to "9" clock dial positions of the dial located by the aforesaid locator punching devices, so that, by noting the positions of the various indicative holes produced by said 15 indicative punching devices relatively to the universal locator holes, the reader may decipher the cryptogram represented.

4. A cryptographic punching means, comprising: universal locator punching devices for locating respectively the center, periphery, and vertical diameter of a clock dial, combined with a set of selective digital indicative punching devices, the set of said indicative punching devices being located in different 20 dial positions on the dial located by the aforesaid locator punching devices, so that, by noting the positions of the various indicative holes produced by said indicative punching devices relatively to the universal 25 locator holes, the reader may decipher the cryptogram represented.

5. A cryptographic marking means, comprising: universal locator markers for locating a clock dial, combined with a set of selective individual indicative markers, the set of said indicative markers being located in the "1" to "9" clock dial positions of the dial located by the aforesaid locator markers, so that, by noting the positions of the various 40 indicative marks produced by said indicative markers relatively to the universal locator marks, the reader may decipher the cryptogram represented.

6. A cryptographic marking means, comprising: universal locator markers for locating a clock dial, combined with a set of selective digital markers, the set of said digital markers being located in the various clock dial positions of the dial located by the aforesaid locator markers, so that, by noting the 50 positions of the various digital marks produced by said digital markers relatively to the universal locator marks, the reader may decipher the cryptogram represented.

60 7. A cryptographic punching means, comprising: universal locator punching devices for locating a clock dial, combined with a set of selective individual indicative punching devices, the set of said indicative punching devices being located in the "1" to "9" 65

clock dial positions of the dial located by the aforesaid locator punching devices, so that, by noting the positions of the various indicative holes produced by said indicative punching devices relatively to the universal locator holes, the reader may decipher the cryptogram represented.

8. A cryptographic punching means, comprising: universal locator punching devices for locating a clock dial, combined with a set of selective digital punching devices, the set of said digital punching devices being located in the various clock dial positions of the dial located by the aforesaid locator punching devices, so that, by noting the 75 positions of the various digital holes produced by said digital punching devices relatively to the universal locator hole, the reader may decipher the cryptogram represented.

9. A cryptographic marking means, comprising: universal locator markers for locating a clock dial, combined with a set of selective individual indicative markers located in the various clock dial positions, and with selective marking means for determining the frequency or the order of reading of the various indicative marks produced by said indicative markers, whereby the reader, by noting the positions of the various indicative marks relatively to the universal locator marks and the frequency or the order indicating mark, may decipher the cryptogram represented.

10. A cryptographic punching means, comprising: universal locator punching devices for locating a clock dial, combined with a set of selective individual indicative punching devices located in the various clock dial positions, and with selective punching means for determining the frequency or the order of reading of the various indicative holes produced by said indicative punching devices, whereby the reader, by noting the positions of the various indicative holes relatively to the universal locator holes and the frequency or the order indicating hole, may decipher the cryptogram represented.

11. A cryptographic marking means, comprising: universal locator markers for locating a clock dial, combined with a set of selective digital indicative markers, the set of said indicative markers being located in different dial positions on the dial located by the aforesaid locator markers, and the locator markers being visually differentiated from the selective digital indicative markers, so that, by noting the positions of the various indicative marks produced by said indicative markers relatively to the visually differentiated universal locator marks, the reader may decipher the cryptogram represented.

In testimony whereof, I have hereunto set my hand.

CHARLES C. MURRAY.
